(57) **CLAIM**

The ornamental design for a case with battery charger for electric toothbrush, as shown and described.

DESCRIPTION

FIG. 1 is a front, right and top perspective view of a case with battery charger for electric toothbrush, showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarge top plan view thereof;

FIG. 8 is an enlarge bottom plan view thereof;

FIG. 9 is a perspective view of the case with battery charger for electric toothbrush with a toothbrush thereof, shown in a separate status; and,

FIG. 10 is a perspective view of the case with battery charger for electric toothbrush thereof, shown in a separate status. The broken lines shown in the drawings illustrate portions of the case with battery charger for electric toothbrush that form no part of the claimed design.
